G. W. RAY

TRACKWAY

Filed March 3, 1927

Inventor

George W. Ray.

By Clarence O'Brien, Attorney

UNITED STATES PATENT OFFICE.

GEORGE W. RAY, OF FORTY FORT, PENNSYLVANIA.

TRACKWAY.

Application filed March 3, 1927. Serial No. 172,410.

The present invention relates to a trackway for railroads and has for its principal object to prevent the pounding of the rails at the junctures thereof which is caused by the ends of the rails giving downwardly as the wheels pass thereover.

Another important object of the invention lies in the provision of a trackway formed with longer ties at the joints of the rails so as to eliminate the tendency of the rails to give downwardly.

With the above and other objects in view as will appear as the description proceeds, the invention resides in certain novel features of construction, and in the combination and arrangement of parts as will be hereinafter more fully described and claimed.

In the drawings:

20 Figure 1 is a plan view of a trackway embodying the features of my invention.

Figure 2 is a transverse section therethrough taken substantially on the line 2—2 of Figure 1.

25 Referring to the drawing in detail it will be seen that the numerals 5 denote the ordinary ties for supporting rails 7. The three ties 8, 9, and 10 adjacent the joints 11 of the rails 7 are longer than the ties 5.

29 The tie 9 is longer than ties 8 and 10. These ties have their ends remote from the joint 11 are in alinement with the ends of the ties 5 so that the other ends thereof extend a greater distance to the side of the track-
35 way than do the ties 5 thereby forming a firmer support for the joints 11 as will be

clearly understood and thereby eliminating to a considerable extent any tendency of the rail-joint to settle or sink into the road-bed vertically at the joints and therefore preventing pounding, or side tipping of loads passing over said joint.

It will be seen that this is a very simple means of overcoming this deficiency in the ordinary trackway.

It is thought that the construction, utility, and the advantages of this structure will now be clearly understood without a more detailed description thereof. It will be apparent that changes in the details of construction may be resorted to without departing from the spirit or scope of the invention as hereinafter claimed or sacrificing any of its advantages.

Having thus described my invention, what I claim as new is:

A trackway of the class described comprising a plurality of ties and a plurality of rails mounted on the ties to be disposed in parallel series, the ties under the adjoining ends of the rails being longer than the remaining ties, said ties below the adjoining portions of the rails extending farther to one side adjacent the joints than to the other side of the adjacent rail, these last-mentioned ties having the center one being longer than the others, said others gradually decreasing in length as they are spaced from the center one.

In testimony whereof I affix my signature.

GEORGE W. RAY.
